HARRY D. GARBER, OF CUYAHOGA FALLS, OHIO, ASSIGNOR TO THE VAN DORN IRON WORKS COMPANY, OF CLEVELAND, OHIO, A CORPORATION OF OHIO

JAIL DOOR MECHANISM

Application filed May 9, 1930. Serial No. 450,992.

This invention relates to controlling mechanism for the sliding doors of a row of jail cells. The mechanism is of the type wherein all of the doors of the row may be locked 5 against closing or against opening, or deadlocked, by gang mechanism; wherein the gang mechanism may be set to allow door movement in one direction but not the other; and wherein the individual doors may be 10 deadlocked independent of the gang mechanism, or the gang mechanism may be set to deadlock all of the doors against the individual door locks.

The object of the invention is to provide 15 of a small number of parts, such a mechanism which shall be simple and rugged and substantially incapable of malfunction.

The exact nature of this invention together 20 with further objects and advantages thereof will be apparent from the following description taken in connection with the accompanying drawings in which Figs. 1 and 2 are front and side elevations respectively of an 25 application illustrative of my invention, parts being broken away to show details of construction; Fig. 3 is a section as in the plane of line 3—3 Fig. 1; Figs. 4, 5 and 6 are views corresponding to Fig. 1 showing the mechanism in as many typical positions; and 30 Fig. 7 is an enlarged detail of parts of the mechanism positioned as in Figs. 1 and 4.

With reference now to the drawings, 1 is a housing arranged along above and in front of a row of jail cells for enclosing the mechanism to be described, a cover not appearing being arranged to close the open front of the housing. Within the housing is the track or runway 2 along which moves a hanger 3 which is provided with a pair of rollers 4 tracking on the runway for the purpose. A 35 barred door 5 is carried by the hanger 3 a portion of which extends downwardly through a suitable slot in the housing 1 for the purpose.

It will be appreciated that whereas only 45 a single door with its immediately associated parts is illustrated, the showing is of one of a number of similar units comprising the usual row of cells.

Secured with the housing 1 is a bracket 6.

The bracket 6 is provided with a pair of vertically extending slot openings 7, spaced in the direction of door movement, and located above the upper extremity of the hanger 3. This upper hanger extremity is 55 toothed as at 8 to present a rack-like formation, and within each of the slot openings 7 is arranged for sliding movement a latch bolt 9, 9a. Each latch bolt is chamfered at its lower extremity as at 10 so that it presents 60 a bevelled face to the teeth 8 of the hanger, and these faces are arranged at opposed angles as indicated.

Each of the latch bolts is provided near 65 its upper extremity with an opening 11. Carried by the bracket 6 is a lever 15 having 70 opposed arms 12 and a downwardly extending arm 13. Each of the arms 12 carries a pin 14 extending into the opening 11 of one of the latch bolts. It will be apparent that 75 by movement of the lever arm 13 the latch bolts may be selectively lowered onto the hanger 3 to engage the teeth of the latter. The openings 11 are much larger than the pins 14 as indicated; so that when the lever 15 is so positioned that the left end latch bolt 9 is lowered, the other latch bolt 9a is raised, and the door may be moved to the left from closed position, but not reclosed; and so that 80 when the lever 15 is so positioned that the right end latch bolt 9a is lowered, the other latch bolt 9 is raised, and the door may be moved to the right from open position, but not reopened; in either case the lowered latch bolt, owing to its chamfered face 10 and 85 the lost motion between its opening 11 and its pin 14, riding over the teeth 8 as the door moved in the allowed direction.

The lower extremity of the arm 13 of the lever 15 has connection with a gang bar 16 running the length of the cell row and having 90 similar connection with the corresponding levers 15 of the other units of the row. The gang bar 16 is provided at one end with suitable operator-controlled means for positioning the bar whereby the described latch bolt means may be set to allow door-closing but not door-opening movement, so that when the door is entirely closed as in Figs. 1 and 4 the door is so locked; or whereby the latch bolt 95

means may be positioned to allow door-opening but not door-closing movement, so that when the door is entirely opened as in Fig. 6 the door is so locked. Also the gang bar may 5 be moved from its position Fig. 4 still further to the left, as in Fig. 5, until the pin 14 moves to the bottom of the opening 11 in the right-hand latch bolt 9a, to deadlock all of the doors of the row or cells.

10 The door 5 carries at its lower extremity a tongue 17 having a pair of notches 18, 19, and aligned with bolts 20 and 21 respectively when the door is closed.

The bolt 20 is associated with the latch bolt 15 9a through a link including the bell crank 22, pull rod 23 and bell crank 24. The bell crank 24 has a pin 25 which fits into a second opening 26 in the latch bolt 9a, similar to but located below the opening 11 therein. The 20 proportion and arrangement of these connecting parts is such that when the gang bar 16 is set as in Figs. 1 and 4 to allow the door to close and there lock it, the bolt 20 will engage the tongue 17 as the door closes, so that the 25 door will be locked closed both top and bottom; but when the gang bar is positioned as in Fig. 6 to allow opening of the doors, the bolt 20 will be raised clear of its notch 18 in the tongue 17.

30 The bolt 20 also carries a projection 27 overlying the bolt 28 of a lock 29 individual to the cell, whereby having a key fitting in the lock 29, the bolt 28 and thus the bolt 20 may be raised from the shown position Fig. 1 to 35 unlock the cell door 5 regardless of the position of the gang bar 16, unless the latter be set as in Fig. 5 to deadlock the row. However, the described control of the bolt 20 by the gang bar 16 may still be had, as the projection 27 may at any time be raised above the bolt 28, by upward movement of the bolt 20.

Beneath the lock 29 is a second lock 30 having a bolt 31 with which the bolt 21 is secured, so that engagement of the bolt 21 with the 45 tongue 17 is controlled by a second key fitting the lock 30. Thus when the cell door 5 is closed it may by the lock 30 be deadlocked against opening, independent of both the gang control mechanism and the lock 29.

50 What I claim is:

1. In combination with a sliding jail door, rack means movable with the door, a pair of latch bolt means mounted for selective cooperation with said rack means, each to prevent 55 movement thereof in one direction, and gang means associated with said latch bolt means for control of the same whereby the door may be selectively secured against opening or closing movement.

60 2. In combination with a sliding jail door, rack means movable with the door, a pair of latch bolt means mounted for selective cooperation with said rack means, each to prevent movement thereof in one direction but allow 65 movement in the other direction, and gang

means associated with said latch bolt means for control of the same whereby the door may be selectively secured against opening or closing movement, said gang means being adapted to deadlock one of said latch bolt means 70 against said rack means whereby the door may be deadlocked against movement in either direction.

3. In combination with a plurality of sliding jail doors, gang means including a pair of latch bolts for each door for securing said doors against opening, said gang means being adapted to deadlock one of the latch bolts of each door, and lock controlled means for individually releasing the doors each from its other latch bolt.

4. In combination with a sliding jail door, rack means movable with the door, latch bolt means mounted for cooperation with said rack means to prevent movement thereof in door-opening direction, gang means associated with said latch bolt means for control of the same and for setting of the same to deadlock said door, additional means for locking the door in closed position, and means associating said latch bolt means with said additional locking means whereby actuation of said gang means to deadlock said latch bolt means prevents unlocking of said additional locking means.

5. Jail door carriage means comprising a hanger member mounted on rollers, means providing a way for said rollers, a door carried by said hanger member, teeth on said hanger member, and means cooperative with 100 said teeth for controlling movement of the hanger on the way and hence corresponding movement of the door.

6. In combination with a sliding jail door, a member movable with the door and provided with teeth, a pair of latch bolts each mounted for sliding movement into the path of said teeth, the bolts having oppositely bevelled faces, and means arranged to lower either latch bolt onto said teeth and providing a lost motion connection with the lowered latch bolt whereby the same may have a ratchet-like engagement with said teeth to allow door movement in one direction but prevent door movement in the other direction.

In testimony whereof I hereby affix my signature.

HARRY D. GARBER.
